POWDER PUFF

Lloyd Orlando Thompson, Monrovia, Calif., assignor of one-third to O. A. Tangren and one-third to Soren O. Thompson, both of Salt Lake City, Utah

Application August 2, 1937, Serial No. 156,909

3 Claims. (Cl. 132—78.5)

My invention relates to improvements in powder puffs and is comprised of outer coverings of transparent silk velvet inside of which is placed three resilient sponge rubber cushions. Two of the rubber cushions or pads are laid together to form one side of an inner bag with the other one rubber cushion or pad forming the other side of the inner bag which is inserted inside the outer coverings of transparent silk velvet. The puff is so constructed that powder can be inserted into the bag formed by the rubber cushions or pads. One of the rubber cushions or pads has a smooth powder proof inner surface which prevents the powder escaping to the back of the puff while the inner of the two rubber cushions or pads which form the other side of the bag is perforated for a powder container. This perforated rubber cushion or pad is adhered to the outer sponge rubber cushion or pad so that the powder from the perforations in the inner pad sifts through to the silk velvet puff covering and thence to the surface to be powdered by the simple operation of patting the puff gently upon that surface.

The powder puff is soft and fluffy and is simple in construction, economical to manufacture, having parts that are readily accessible. The puff is handy to use and economical in that it will save powder. Powder will emit from the puff as long as any remains in the puff center, which is easy to re-fill with a fresh new portion of powder. One filling of the puff center will supply ample powder for several make-ups.

The puff consists of certain novel features of construction and utility as will hereinafter appear as this description proceeds.

The accompanying drawings are explained as follows:

Figure 1 is the top plan view of the powder sifting side of the puff;

Figure 2 is a view looking into the end in which the powder is inserted into the puff interior;

Figure 3 is an edge view of the puff;

Figure 4 is an inverted view of Figure 1;

Figure 5 is an enlarged cross-section view on line 5—5 of Figure 4;

Figure 6 is a plan view of the top sifting sponge rubber pad which lies between the outer silk velvet covering Figure 1 and the perforated pad, Figure 8;

Figure 7 is an end view of Figures 6, 8 and 9 as placed together for insertion into the outer silk velvet covering;

Figure 8 is a plan view of the perforated sponge rubber pad;

Figure 9 is a plan view of the back pad inside Figure 5;

Figure 10 is an exploded view of the three sponge rubber pads used to make up the entire inner powder container and sifter;

Figure 11 is a plan view of one side of the silk velvet powder puff cover;

Figure 12 is a view of one of the reinforcing strips;

Figure 13 is a view of finger ribbon.

In constructing this puff the outer silk velvet coverings (Figure 11) at 3 are cut in the desired shape and size and a fine leather strip (Figure 12) is sewed to the upper inner edge of each of these coverings at edge 1—1 of the leather strip (Figure 12) to edge 2—2 of outer covering 2 (Figure 11) so that the wider edge of the leather strips turn down inside the bag formed by sewing the two outer coverings together around the curved edges leaving the opening along line 2—2 of the outer coverings as shown by 6 in Figure 2. In the process of sewing the two outer coverings together the finger ribbon 4 in Figure 13, is, at the same time, sewed to the two silk velvet coverings so that the ends of the ribbon are between the edges of the outer coverings as shown in Figure 3 at 4 and forming a finger strip as shown in Figure 4 at 4. In the sewing process the silk velvet coverings are turned face in and after being sewed together are then turned out so that the raw edges of the sewing are inside the bag thus formed and placing the fine leather strips inside this bag to be used as flaps to divide and hold in place the inner sponge rubber cushions or pads.

The inner portion of the puff consists of three resilient porous rubber cushions or pads of the same shape and perimeter.

In constructing the inner portion of the puff, sponge rubber pad, Figure 6, is cemented to the perforated sponge rubber pad, Figure 8. The inside outer edge of the perforated sponge rubber pad, Figure 8, is then cemented to the inside outer edge of sponge rubber pad, Figure 9, leaving end opening between the straight ends, so that a pocket is formed as shown by 6 in Figure 7 and 6 in Figure 5. The sponge rubber powder pocket formed as last above stated is then placed within the outer silk velvet coverings so that the opening to the resilient porous rubber pocket is just inside the opening of the outer covering and the two fine leather strips are extended down inside the pocket formed by cementing the inside outer edges of the perforated sponge rubber pad, Figure 8, to the inside outer edge of sponge rubber pad,

Figure 9. The outer silk velvet covering, the leather strips and the inner resilient porous rubber portions are then securely joined together by sewing as shown by 10 in Figure 1 and 10 in Figure 3.

Figure 5 shows in detail the cross section of the complete puff as on line 5—5 Figure 4. Explaining Figure 5, 3 is the outer silk velvet covering sewed at 11 with edges turned in abutting inner 10 resilient porous rubber pad; 7 is the porous, sifting rubber pad which permits emission of powder from the perforations in resilient porous rubber pad 8; 12 is the outer edge where resilient sponge rubber pad 8 is connected to resilient porous rubber pad 9 forming the pocket 6 where powder is retained; 9 has a smooth rubber surface inside powder retaining pocket which prevents powder escaping through rubber pad 9 to the back of the puff.

20 I claim.

1. A powder puff of the class described, comprising a resilient member having a powder receiving pocket therein, with the mouth of the pocket opening out through an edge portion of 25 the member, one side wall of the pocket having perforations therein, a porous member covering said side wall, a fabric covering for said members, formed of porous fabric and having an opening in an edge portion thereof adjacent the

mouth of the pocket and flap means for closing said opening.

2. A powder puff of the class described, comprising a pair of members formed of rubber and having their edge portions connected together to 5 form a pocket for receiving powder, one member having perforations therein, a third member of porous rubber connected to the perforated member and covering means for the members formed of porous fabric.

3. A powder puff of the class described comprising a pair of members formed of sponge rubber, connected together at portions of their edge parts to form a powder receiving pocket the unconnected portions forming a mouth for the 15 pocket, one member having perforations therein and the inner face of the other member being non-porous, a third member of sponge rubber connected with and covering the outer face of the perforated member and a bag in which the 20 members are placed, said bag being formed of transparent cloth material having a nap on its outer side and said material being porous for the passage of the powder therethrough, said bag having an opening in a portion of its edge, located adjacent the mouth of the pocket and flap means for covering the opening.

LLOYD ORLANDO THOMPSON.
